United States Patent

Des. 241,537
Patented Sept. 21, 1976

241,537

FILM LOADING CONSOLE OR THE LIKE

Richard J. Olson, Pittsford, N.Y., assignor to Eastman
Kodak Company, Rochester, N.Y.

Filed Apr. 10, 1975, Ser. No. 567,941

Term of patent 14 years

Int. Cl. D16—04

U.S. Cl. D16—34

FIG. I

FIG.2

FIG. 3

FIG. 4

FIG. 5

FIG. 1 is a right side and front perspective view of a film loading console showing my new design;
FIG. 2 is a left side and rear perspective view thereof;
FIG. 3 is a right side elevational view thereof;
FIG. 4 is a top plan view thereof; and
FIG. 5 is a bottom plan view thereof.

I claim:

The ornamental design for a film loading console or the like, as shown.
